United States Patent Office

Des. 175,374

Patented Aug. 16, 1955

175,374

ROD HOLDER

Ervin D. Stroud, Houston, Tex.

Application December 3, 1954, Serial No. 33,391

Term of patent 14 years

(Cl. D31—4)

Fig. 1

Fig. 2

Fig. 3

Fig. 1 is a side elevational view of a rod holder, showing my new design; Fig. 2 is a rear elevational view of the upper portion thereof; and Fig. 3 is a plan view thereof.

The fragmentary portion of a rod shown in Figure 1 by means of broken lines is disclosed for illustrative purposes only.

I claim:

The ornamental design for a rod holder, as shown and described.
